UNITED STATES PATENT OFFICE.

ORAMILLE C. CARPENTER, OF BROOKLYN, NEW YORK, ASSIGNOR TO
NATHANIEL B. ABBOTT, OF SAME PLACE.

MACHINE FOR WIRING CORKS IN BOTTLES.

SPECIFICATION forming part of Letters Patent No. 295,735, dated March 25, 1884.

Application filed December 17, 1883. (No model.)

To all whom it may concern:

Be it known that I, ORAMILLE C. CARPENTER, of the city of Brooklyn, in the county of Kings and State of New York, have invented 5
a new and useful Improvement in Machines for Wiring the Corks in Bottles; and I hereby declare the following to be a full and clear description thereof.

The object of this invention is to construct 10
a machine for putting wires over the tops of corks in bottles and twist the said wires with wires which are placed by the machine around the necks of the bottles, so as to hold the corks in their positions in the bottles.

15 The construction and operation of the said machine will be readily understood by reference to the accompanying drawings, in which—

Figure 1 is a side elevation of the complete machine. Fig. 2 is a longitudinal sectional elevation of it. Fig. 3 is a general plan. Fig. 4 is a front end elevation. Fig. 5 is a transverse sectional elevation of the machine, taken on the line *x x* of Fig. 1, and looking toward the rear end of the machine. Fig. 6 is a rear end elevation of the machine. Fig. 7 is a transverse sectional elevation of the machine on the line *y y* of Fig. 1, and looking toward the front end of the machine, so as to show the cutting-off shears. Fig. 8 is a detailed plan of the 25
sliding shaft and its attached operating-jaws which hold and twist the wire. Fig. 9 is a longitudinal sectional elevation of the parts shown in Fig. 8. Fig. 9^x is a partial section of Fig. 9 on line *x x*, looking toward the front or closing end of the jaws. Fig. 9^{xx} is a similar section, looking in the opposite direction; Fig. 10, an enlarged sectional view of spring- 30
catch mechanism. Fig. 11 is a detailed view of sliding follower and clamps. Fig. 12 is a detail view, showing the mechanism in section for clutching the gears *B⁴* and *B⁵*. Fig. 13 is a detailed view of the spring for allowing the lateral movement of the nippers.

All of the operative parts of the machine 45
are attached to or supported by the bed-plate or table *A*, which, when the machine is in operation, is raised up on legs or other supports, *a*, so as to make the top of the table or bed-plate stand at an elevation of about three feet 50
(more or less) from the floor on which the operator stands.

Secured to the top of the bed-plate or table *A* are stands or bearing-supports *A' A²* for the journal-bearings of the shaft *B* and for other purposes. The front one of these supports, *A'*, besides furnishing a bearing for the said driving-shaft, also provides bearings for the nippers for holding the front end of the twisted wire in proper position with respect to the cork of the bottle and the cam for operating said nippers; also the shears for cutting off the wire after it is twisted properly on the bottle; and likewise the holder of the mouth of the bottle when it is placed in the machine, all of which specific parts of the machine will 65
be presently described.

The shaft *B*, besides having on it the driving gear-wheel *B'*, by which it is driven, carries a cam, *B²*, for imparting a longitudinal movement to the sliding shaft and its attached wiring-jaws, as hereinafter described, and also a gear-wheel, *B³*, for driving through a train of gearing the sliding shaft and its attached jaws, when it is required to rotate the said sliding shaft, as hereinafter described. The 70
sliding shaft *C* has its bearing in a sliding head, *C'*, which is seated in the stand *A²*, bolted to the bed-plate *A*. The said shaft is rotated in the said sliding head *C'* by means of a gear-wheel, *C²*, which is actuated by the train of 75
gearing hereinafter described, the said gear-wheel *C²* allowing the shaft *C* to slide longitudinally within it by means of a longitudinal groove, *C⁵*, in the periphery of the said shaft, and a key or tongue attached to the said wheel 80
C² and depending into the said longitudinal groove. A standard, *C¹*, bolted to the bed-plate *A*, is secured to the yoke *C³*, which embraces the wheel *C²*, thus providing against any lateral movement of the latter upon the 85
shaft *C*. The sliding head *C'* is moved longitudinally in the machine by means of a follower or lever, *D*, and its actuating-cam *B²*. The upper end of the said follower or lever is attached to the sliding head *C'* by means of a 90
link, *d*, so as to allow the sliding head to move in a straight line, while the top end of the said lever describes a small arc of a circle. The lower end of the said lever or follower is slotted for the fulcrum-pin *d'*, and the fulcrum-lug *A³*, to which it is fulcrumed, is also 95
slotted vertically, so as to move the fulcrum-

pin up or down, as occasion may require, to increase or diminish the length of throw of the top end of the lever or follower, and consequently the amount of longitudinal movement of the sliding head C'. This is for adjusting the machine to different work or different-sized bottles. A pin or sheave, D', attached to the said follower or lever D, is engaged by the rotating cam B² and moved as the said cam rotates, so as to carry the sliding head C' forward and backward at each rotation of the said cam B². The operating-jaws E E (which carry the wire to and twist it around the neck of the bottle) are attached to the front end of the sliding shaft C, and moved forward and backward, and rotated by and with the said shaft. The cam B² is constructed so as to move the sliding shaft and its operating-jaws forward and backward quickly for the most of the longitudinal movement, and then slowly forward for a short distance, so as to accommodate the jaws to the operation of twisting the wire on the bottle, the jaws being required to move toward the bottle as the act of twisting the wire shortens it, and consequently the distance between the jaws and the bottle. The quick-moving part of the cam is shown in Fig. 1, between the points b and b', while all of the rest of the periphery of the cam—i. e., between the points b' and b—the cam is made so as to move the lever D and its attached parts just enough to accommodate the jaws to the twisting movement above described. The operating-jaws E are pivoted at e, near their central part, to a transverse bar or head, E', which is securely fixed to the front end of the sliding shaft C. The front ends of the said jaws are arranged to close tightly together, as shown in Figs. 3 and 8, and the rear ends of them are separated several inches apart, and attached by the follower-links E² E² to a sliding collar, E³, which slides on the sliding shaft C. The opposite ends of the links E² E² are respectively attached, by hinge-joints or pivot-pins e' e'', to the jaw-pieces E and the sliding collar E³. This construction of the operating-jaws and the open position of the said jaws are shown in dotted lines, and the closed position by the full lines, in Fig. 8. A coiled spring, E⁴, surrounds the sliding shaft C, in front of and pressing against the sliding collar E³, to press it back and open the jaws, when the spring-catch e³, shown in Fig. 10, releases the said sliding collar at the extreme forward limit of its movement, as presently explained. When the sliding shaft C is moved backward, just before it reaches the extreme limit of its movement, the rear end of the sliding collar E³ strikes the stop E⁵, and then the continued rearward movement of the said shaft causes the said collar to slide relatively forward on it, and thus close the jaws, and as soon as they are closed the spring-catch e³ engages in a notch or hole 65 in the shaft C, and thereby holds the jaws closed tightly until they make their next full movement forward; and then, just as soon as the nippers F grasp the wire which projects in front of the ends of the operating-jaws, the tappet h (connected with and operated by the lifting table G) releases the spring-detent e³ and allows the spring E⁴ to throw the jaws open; and as soon as the jaws are thus opened they are moved rearward by and with the shaft C until the stop E⁵ closes them again, as above 70 described. The stop E⁵ is made adjustable, so as to close the jaws at any desired point. The mechanism of the other parts of the machine is such that as soon as the jaws E are closed the shaft C, to which they are attached, commences to rotate, and this rotation of the said jaws twists the wires between the bottle and the end of the jaws just enough to tighten the wire on the cork, and during this twisting operation the cam B² moves the jaws just far 75 enough ahead to take up the shortening distance made by the twisting wire. The rotation and forward and rearward movements of the shaft C are made by the gearing and cam-connections between the two shafts, so that at 80 each revolution of the driving-shaft B the sliding shaft C makes one complete movement forward and backward, and a sufficient number of rotations to thoroughly twist and tighten the wire on the cork in one bottle, and the 85 length of the throw of the said shaft backward and forward is just enough to feed out through the jaws E wire enough to cork one bottle. The bottle to be corked or wired is placed on the table G, which slides up and down in 90 ways g, and is moved up by treadle G', lever G², and connecting-rods G³ G⁴. The weight W at the rear end of the lever G² acts as a counter-weight to help raise or balance the table. A sliding rod, H, actuated by the 95 cam-faced attachment 2 of the table G extends longitudinally therefrom through the machine in any convenient or suitable location, and actuates the tappet h and the clutch H' at the proper moment to make the mechanism 100 of the machine act in harmony with the movements of the said bottle-table, and thereby places all of the movements of the machine automatically under the control of the operator, who moves the treadle G' and places the 105 bottles on the table G. In utilizing this provision of the machine, a bracket or arm, F', attached to the table G, is connected by a connecting-rod, F², with the cam F³, which operates the nippers F, to close them tightly on the 110 wires X as soon as the said wires are thrown forward far enough for the nippers to receive them. The cam F³ is constructed, as shown in Fig. 4, so as to close the nippers F before the table G reaches the full upward limit of 115 its movement, and hold the nippers closed until the wire is affixed to the bottle enough to hold it in place. The nippers are habitually thrown open by the spring f, which holds the said nippers open until the cam F³ closes 120 them again. The nippers F are fulcrumed to the strap f', which said strap is hung on 125 130

a pin, f^2 , which projects from the front of the support or standard A' . The pin f^2 is made long enough to allow the strap f' , with the nippers, considerable lateral movement, for the purpose of preventing the nippers from interfering with the removal of a bottle from the machine; but a spring (see Fig. 14) habitually throws the nippers F up against the machine or the support A' . The clutch H' , operated by the sliding rod H , couples the gear-wheel I to the driving-shaft I' , so as to start the rotary mechanism of the machine at the proper moment the position of the table G (with a bottle on it) requires the rotary movements of the machine to commence to harmonize the whole operations of the machine. The shaft I' is to run continuously by means of a belt or gear-wheel, (not shown,) but by means of the clutch H' the shaft B , with all the mechanisms operated by it, is started and stopped with each raising and lowering of the table G . The wires $x^1 x^2 x^3 x^4$, which are used with this machine are carried on the spools $J' J^2 J^3 J^4$, the two first of which are attached to the opposite sides of the jaws E , and feed their wires forward through transverse holes in the jaws E , as shown in Fig. 3. The two latter-named spools are attached to the rear end of the sliding shaft C , which is made hollow, and the wires $x^3 x^4$ are passed through this hollow shaft to the jaws E , where all of the wires used unite and are twisted into a wire cord, X , which forms the wiring of the bottle. There may be two or more of these wires used at one time. Where four wires are used the complete wire X is branched off from the nippers, (which hold it during the wiring operation,) two wires, $x^1 x^2$, passing around the bottle-neck, and the wires $x^3 x^4$ over the cork. Where only two of the wires are used the spools not in use will simply remain idle. All of the spools are attached to the machine so as to counterbalance each other on the jaws or shaft, as the case may be.

The wires attached to the machine, as above described, and united in and twisted by the jaws E , are applied to the top of a bottle as follows: The front ends of the several wires in the first instance are twisted up tightly by hand, just in front of the jaws E in the first instance—*i. e.*, on starting a new set of wires—but after that the machine does all the twisting. The twisted ends of the wires X , when the jaws are thrown forward, are grasped by the nippers F , and just a moment later the table G , with a bottle on it, is raised up so as to press the top of the bottle, with a cork in it, up under the wires $x^3 x^4$ and between the jaws E carrying wires $x^1 x^2$. The mechanism of the parts is such that just an instant later than the time the top end of the cork in the bottle strikes the wire between the jaws E the said jaws are opened by the tappet h , releasing the spring-detent e' , and allowing the spring E' to throw the jaws open. The continued rising of the table G still a moment later also

carries the mouth of the bottle still farther up between the jaws, and this helps also to open the jaws E . The wires $x^3 x^4$, thrown over the cork of the bottle in this manner, are caught between the top end of the cork and the bottom end of the spring-follower K , which slides in the vertical chamber A^4 of the arm or standard A' . This sliding follower, thrown down by the spring h , permits the top end of the bottle, when pressed upward by the table G , to rise up into the lower end of the cavity of said chamber A^4 , and carry the wires $x^3 x^4$ over the cork along with it, the follower K meanwhile holding the wires down on the cork of the bottle, but permitting them to slide over it as the bottle is raised. The front end of the wire, however, is meanwhile held between the nippers F . A pair of clamps, $k' k^2$, as shown in detail, Fig. 11, are hinged to the bottom end of the follower K , and thrown down by small springs, so as to allow the wires to pass between them when they are opened, but centering the wires over the corks when the bottle is raised up, the said clamps closing up with the wires between them when the top end of the cork or bottle strikes them in its upward movement. The front edges of the said clamps are beveled, so as to allow the wires to slip down off of them when the table is lowered. A spring catch or clamp, L , is also attached to the arm A' , which catches under the neck of the bottle when the table G is lowered, and holds the bottle just in the proper position for allowing the wires to be twisted around the neck of the bottle just below its flange or wiring-lock. This feature of the machine adapts it to long or short necked bottles.

For the purpose of forcing the loose wires at the rear side of the bottle down to the wiring neck of the bottle when the jaws are thrown back and opened, a finger, M , is pivoted to the cross-bar of the jaws and arranged to be thrown down in front of and between the jaws E , when they are opened, so that the front end of this finger can press the wires down at that moment to their proper position. This finger is thrown upward by a spring, m , and is thrown forward and down at the proper moment by the sliding rod M' , a pawl or detent, m' , on said rod engaging with a pin, m^2 , on the finger-bar, as shown in Figs. 8 and 9. The method of moving said rod M is also shown in said Figs. 8 and 9.

M^2 is a lever pivoted to the rod M' , and also to a projection, M^3 , on the shaft C . The lower end of lever M^2 abuts against a stop, M^4 . The arrangement is such that when the jaws recede the lever M^2 will act to throw the rod M' forward and depress the finger-bar, as before explained. The sliding rod M' is held in position next the shaft C by loop q^3 , or in other suitable manner, and is moved by lever M^2 , which is loosely pivoted to said sliding rod, and is pivotally supported by bracket M^3 , extending from the shaft. A pair of shears, N ,

attached to the inside of the standard or arm A', cut off the twisted wires between the bottle and the ends of the nippers as soon as each bottle is wired. This leaves a small twisted 5 wire cord projecting a little beyond the ends of the nippers for the next bottle. The nippers are operated just at the proper time for this purpose by the rod N' and cam N², the said cam being placed on the shaft B and operated by it. As has before been stated, this shaft makes one revolution at each full stroke or operation of the machine, so, of course, the cam N² can easily be set to operate the shears N just as the twisting of the wire is completed. 15 The sliding shaft C is rotated by the wheel C², which is driven, through the train of gearing B⁵ B⁴ B³, from the shaft B. The wheel C² has a tongue, b, which enters a longitudinal groove in the shaft C, and this construction allows the shaft to slide in the said wheel when the sliding movement before alluded to occurs, and at the same time provides an engagement for the said wheel for the rotation of the shaft when it is required. A clutch, B¹, 20 on the gear-wheel B³, is thrown into engagement by the cam B⁸ on the shaft B, so as to clutch the wheels B⁵ and B⁴ together at the proper time to rotate the shaft C. When not so clutched together, one or the other of the 25 wheels B⁴ B⁵ will stand idly on its shaft, which will be allowed to rotate idly within it. The cam B⁸ on the shaft B is arranged to engage its clutch in that portion of the rotation of the shaft B which is proper for the rotation 30 of the shaft C, as hereinbefore specified. The gears B⁴ and B⁵ are mounted upon a counter-shaft, B⁹. The clutch B¹, operated by the cam B⁸, is provided with a pin resting within an aperture in the wheel B⁵. A spring ordinarily 35 keeps the clutch from engagement with gear B⁴; but in the revolution of the cam B⁸ it strikes the clutch and forces its projecting pin inwardly, through the gear B⁵, into contact with gear B⁴, thereby clutching the two gears, for 40 the purpose heretofore described.

Having described my invention, I claim—

1. In a bottle-cork-wiring machine, the combination of a pair of movable jaws with a rotating and sliding shaft to which the jaws 50 are attached, mechanism, as described, for opening and closing the jaws, and a cam rotated by a train of gearing for moving the jaws longitudinally, whereby the sliding and rotating movements of the said jaws, together with 55 their opening and closing movements, complete the wiring of a cork, automatically, at one operation.

2. The sliding and rotating shaft C, provided with wiring-jaws E, in combination 60 with the sliding collar E³, stop E⁵, and spring E⁴, and the detent e¹, with means for operating the detent, whereby the movements of the jaws are controlled by the sliding shaft and the detent, as described.

65 3. A vertically-moving finger or wire-depressor pivoted to the transverse bar or frame

of the movable jaws of a bottle-wiring machine, in combination with a sliding bar for actuating the finger, operated by the longitudinal movement of the said jaws, and a lever-connection, as described, so as to throw the wire down to the flange of the neck of the bottle at each stroke of the machine before the twisting of the wire commences. 70

4. The vertically-moving finger, M, the 75 sliding operating-bar M' for moving the said finger M, and the detent or pawl m' and operating-pin m², in combination with the pivoted lever M², constructed and operated as described. 80

5. The cam B², pivoted lever D, sliding shaft C, with its attached movable jaws E, opening-spring E¹, and closing stop collar and abutment E³ E⁵, combined and arranged so that at each revolution of the cam B² the 85 sliding shaft, with its attached movable jaws, shall make one forward and backward movement, with the necessary opening and closing of the said jaws, at each revolution of the cam. 90

6. The combination of the driving-shaft B and sliding shaft C, and its attached gears, connected together by the gearing-train B³ B⁴ B⁵ C², whereby the sliding shaft and its attached jaws are rotated a sufficient number of 95 times to thoroughly twist and tighten the wire on the bottle during a fractional portion of the revolution of the driving-shaft, and the forward and backward movement of the sliding shaft is effected during the remainder of the 100 rotation of the driving-shaft.

7. The vertically-sliding table G, having cam-faced attachment 2, the sliding rod H, arranged, as described, so as to be shifted by the engagement of said attachment 2 therewith, 105 and devices, substantially as described, connecting the sliding rod H with the jaw-operating mechanism, whereby the jaws are thrown into operation by the reciprocation of table G, all the recited elements in combination, as and 110 for the purposes set forth.

8. The spring-clamp L, attached to bottle-mouth holder A' K, so as to clasp the neck of bottle just below the flange thereof, and hold the bottle by the top end of its neck during 115 the wiring operation.

9. The automatic wire-holders k' k², for centering the wires over the cork, the said holders hinged to the bottom of the spring-follower of the bottle-mouth holder, and provided with springs for automatically closing the said wire-holders on the wires, and with bevel-edged lips to allow the wires to escape from the said holders when the wires are drawn down tightly on the corks of the bottles. 120

10. In combination with the reciprocating table, the sliding and rotating jaws and their operative mechanism, substantially as described, arranged at one side of said table, 130 and the nippers F at the other side of said table, said nippers provided with operative

mechanism, substantially as described, by which they are operated to grasp the wires projecting from said jaws and hold them during the backward movement of the jaws, substantially as set forth.

11. The automatic nippers F, their operating-cam F³, connecting-rod F², and the bottle-holding table, combined substantially as described and set forth.

12. The combination of jaws E, nippers F, and shears N, with means, substantially as described, for operating the same, arranged as set forth.

O. C. CARPENTER.
